UNITED STATES PATENT OFFICE

GEORGE HENRY WHEARY, OF RACINE, WISCONSIN, ASSIGNOR TO WHEARY TRUNK COMPANY, OF RACINE, WISCONSIN, A COMPANY OF WISCONSIN

HAND LUGGAGE

Application filed February 18, 1931. Serial No. 516,587.

This invention relates to certain new and useful improvements in hand luggage and relates particularly to ladies' hand luggage.

A general object of this invention is to provide greater convenience in packing or placing the garments in a luggage carrier and in removing them from the case.

Another object is to provide a ladies' hand case in which garments and particularly ladies' dresses of any length may be carried without wrinkling and without necessitating the alteration in any respect of the over-all size of the case.

Another object of this invention is to provide a novel and improved garment supporting structure for a ladies' hand case which is of extremely simple construction and has an individual hanger or support for each garment.

Another object of this invention resides in the provision of individual garment supports carried by a frame of the type illustrated in the copending application of George Henry Wheary and Benjamin M. Hamlin, Serial No. 357,088, and so located that the effective hanging length for garments is materially increased to thus accommodate the modern long dresses.

And a more specific object of this invention resides in the provision of means for mounting a plurality of individual garment supports from a frame of the type shown in the above mentioned copending application and located at a point adjacent the hinged mounting of the frame.

With the above and other objects in view which will appear as the description proceeds, my invention resides in the novel construction, combination and arrangement of parts substantially as hereinafter described and more particularly defined by the appended claims, it being understood that such changes in the precise embodiment of the hereinabove closed invention may be made as come within the scope of the claims.

In the accompanying drawings, I have illustrated one complete example of the physical embodiment of my invention constructed according to the best modes I have so far de-

vised for the practical application of the principles thereof, and in which:

Figure 1 is a perspective view of a lady's hand case embodying my invention shown in open position and illustrating the manner of packing garments therein;

Figure 2 is a view partially in end elevation and partially in transverse section showing the manner in which the garments are supported;

Figure 3 is an enlarged detail perspective view showing a portion of the garment supporting frame and part of one of the garment supports;

Figure 4 is a view similar to Figure 2 illustrating a slightly modified form of my invention;

Figure 5 is a perspective view similar to Figure 1 of another modification of my invention;

Figure 6 is a view partially in end elevation and partially in transverse section of that form of my invention shown in Figure 5; and

Figure 7 is a fragmentary detail in perspective showing the garment frame support.

Referring now more particularly to the accompanying drawings, in which like numerals represent like parts, the numeral 5 represents the main section of a lady's hand luggage having a cover 6 hingedly connected thereto along one marginal edge, as at 7, and as is customary, the case is provided with a conventional handle 8 and locking means 9.

The main section of the case preferably has a partition 10 which is removably mounted therein parallel with its rear wall or panel 11 and spaced therefrom to provide a well 12 for the reception of the depending ends of garments 13 carried in the case. The garments 13 are conveniently supported on a garment carrying frame 14 consisting of a substantially U shaped member comprising side arms 15 connected at their outer ends by a transverse bar or rod 16 and having their inner end portions 17 directed inwardly and upwardly at an angle with respect to the plane of the frame proper when in a horizontal position over the main section.

The end portions 17 of the garment carry-

ing frame are pivotally connected as at 18 with attaching members 19 the upper ends 20 of which are likewise angularly directed. The lower ends of the attaching members are 30 removably secured, to the side walls of the main section and in this manner the garment carrying frame is pivotally mounted and may be swung into and out of alignment with either the main section or the cover when the 10 case is open.

In the copending application above referred to, the garments are draped, at a medial point, over the transverse member 16 of the garment carrying frame with their depending ends at opposite sides of the frame to extend into the well 12. A number of garments may be similarly carried on the frame, one being placed above the other, and while this method of packing is satisfactory, where 15 the total length of the garments is not greater than twice the distance from the transverse member 16 to the bottom of the well 12 when the frame is in a vertical position, the exceptionally long dresses decreed by modern 20 fashion cannot be accommodated in this manner without increasing the dimensions of the case or crumpling the ends of the garments.

Also, when all of the garments are supported solely by the bar 16, it is difficult to 30 remove any single garment, and this invention, therefore, contemplates the provision of simple but effective means whereby longer garments may be readily accommodated without in any wise changing the size of the case 35 or the garment carrying frame and without wrinkling and whereby an individual garment support is provided for each garment.

To this end the side arms 15 of the frame have laterally extended arms 21 secured to 40 their inner faces by rivets 22 or the like, at aligned points adjacent their hinged connection with the attaching members 19. The lateral arms 21 have their outermost ends provided with sidewise extended projections 23 45 so that the arms are substantially T shaped.

Engageable with the lateral arms, are a plurality of garment carrying members 24 which may be of any desired construction and in the present instance, consist of relatively 50 thin strips of wood or metal provided at their ends with attaching members 25, preferably stamped from metal and having elongated apertures 26 in which the lateral arms 21 are receivable so that the garment carrying members 24 are detachably engageable with the arms 21. The length of the slots 26 at the ends of the members 24 is less than the overall width of the extreme outer ends of the arms 21, but is sufficient to permit the members 24 to be engaged with the arms 21 by engaging first one of the side projections 23 in the slot 26 and then the other, as will be readily apparent.

In packing dresses and other garments, the 65 case is positioned as illustrated in Figure 1

with the frame 14 in its horizontal position and the cover open. A single dress or other garment is then draped over each member 24 at a substantially medial portion so that the total length of the dress is divided in two. 70 With the garments thus positioned on the supports 24 the supports are engaged with the arms 21 one above the other, and the dresses or other garments thereon are neatly arranged over the front portion of the case as illustrated in Figure 1, and when all of the garments are thus positioned, the frame 14 is raised so that the garments are caused to fold or drape themselves over the outer transverse bar 16 of the frame. 75

Two or more garment retaining bars 27 are then engaged with the side arms 14 in the conventional manner to retain the garments against dropping into the interior of the main section when the frame is returned to its horizontal position over the main section preparatory to closing the case. The garments thus form an internal cover for the main section of the case and if desired, a more suitable cover 28 may be provided as illustrated in 80 Figure 4.

The cover 28 shown in this disclosure of the interior has its inner end provided with a downwardly curved portion 29 which is hingedly connected with the partition 10, the 85 curved portion 29 precluding the possibility of creasing the garments at their portions extended into the well 12.

As illustrated in Figures 5 and 6, this invention also lends itself particularly well to 100 hand luggage in which it is desired to position the entire garment carrying structure within the cover. In this instance, as in the embodiment illustrated in Figures 1, 2, and 3, the garment supporting frame consists of side 105 members connected at their outer ends by a transverse garment receiving bar, but instead of mounting the frame from attaching members secured to the sides of the main section, the inner ends of the frame arms are directly 110 pivoted to the side walls 30 of the cover as at 31. The point of pivotal connection 31, however, is closely adjacent the hinge connection 7, between the main section and the cover, and the manner of packing or arranging the garments on the carrying frame is similar to that described in connection with the embodiment shown in Figure 1, i. e. each garment is 115 draped over an individual supporting bar which is then connected with the lateral arms 120 21.

The garments are also draped over the transverse bar of the frame, but in place of the retaining bars 27 the garments are held against dropping down into the main section, 125 when the case is closed, by an internal cover 32 hingedly mounted as at 33 from the rear wall 34 of the cover adjacent its hinged connection 7 with the main section.

The internal cover 32 is sufficiently large to 130

substantially close the open front of the cover and thus completely enclose the garments in the cover. Any suitable means may be provided for releasably holding the internal cover closed and in the present instance a conventional snap fastening 35 carried by a flexible strap 36 is provided at the outer free end of the cover.

It is noted that in this embodiment the case 10 is slightly increased in over-all dimensions to enable the garments to be entirely received within the cover without wrinkling their depending ends and that the necessity for a well adjacent the rear of the main section is thereby obviated. The interior of the main section 15 may be divided to suit any particular requirement for which the case may be designed and in the structure illustrated a removable partition 37 is provided near the front wall 20 of the main section.

From the foregoing description taken in connection with the accompanying drawings, it will be readily apparent to those skilled in the art to which an invention of this character appertains, that I provide an exceptionally convenient garment supporting structure for ladies' hand luggage in which dresses and other garments of any practical length may be accommodated without necessitating an increase in the overall dimensions of the case and without wrinkling the garments. It is also apparent that packing and removal of individual garments is facilitated by the provision of individual garment supports for all of the garments carried.

What I claim as my invention is:

1. In a case type luggage including hinged- 40 ly connected sections, a garment carrying frame comprising side arms having their outer ends connected by a transverse member over which garments may be draped, means pivotally mounting the garment carrying frame for movement about an axis adjacent to and substantially parallel with the axis of the hinged connection of said sections, individual garment supports adapted to have garments draped thereover preparatory to being draped over the transverse member at the outer end of the garment supporting frame, 50 and means carried by the frame adjacent its pivotal mounting for readily detachably mounting the individual garment supports in superimposed relation.

2. In a hand luggage of the case type in- 55 cluding hingedly connected sections, a garment carrying frame having a transverse garment receiving member, means hingedly mounting the frame for movement about an axis adjacent to and substantially parallel with the hinged connection of the case sections, individual garment supports over which garments may be draped preparatory to being draped over the transverse member of the garment receiving frame, and common 65 means for readily detachably mounting all

of the individual garment supports on the garment carrying frame.

3. In a hand luggage of the case type in- 70 cluding hingedly connected sections, a garment carrying frame hingedly mounted for movement to and from alignment with either section when the case is open, said garment carrying frame having a transverse garment receiving member, individual garment sup- 75 ports adapted to have garments draped thereover preparatory to being draped over the transverse garment receiving member of the garment carrying frame, and common means for readily detachably mounting the individual garment supports from the garment carrying frame adjacent its hinged mount- 80 ing.

4. In a hand luggage of the case type in- 85 cluding hingedly connected complementary sections, a garment carrying frame comprising side arms connected at their outer ends by a transverse garment receiving bar over which garments may be draped, means for pivotally mounting the inner ends of the side arms adjacent the hinged connection of the complementary sections whereby the frame may be swung into alignment with either section when the case is open, individual garment supports adapted to extend across the 90 space between the side arms and over which garments may be draped preparatory to being draped over the frame transverse bar, and means carried by the side arms of the frame adjacent their hinged mounting with which the ends of the individual garment supports are engageable in superimposed re- 95 lation.

5. In a hand luggage of the case type in- 100 cluding hingedly connected sections, a garment carrying frame hingedly mounted in one of the sections adjacent its hinged connection with the other section, said garment carrying frame including side arms and a transverse garment receiving bar connecting the side arms and over which garments may be draped, individual garment supports adapted to have garments draped thereon preparatory to being draped over the trans- 105 verse frame bar, lateral extensions carried by the side arms adjacent their hinged mounting, and means at the outer ends of the garment supports adapted for readily detachable connection with the lateral extension, whereby the garment supports are 110 mounted in superimposed relation.

6. In a hand luggage of the case type in- 115 cluding hingedly connected sections, a garment carrying frame comprising side arms connected at their outer ends by a transverse garment receiving bar, means pivotally connecting the inner ends of the side arms with one of the sections adjacent its hinged connection with the other section, a plurality of individual garment supports each adapted to have a garment draped thereover parallel 120 125 130

laterally extended arms carried by the side arms of the garment carrying frame adjacent their inner ends, means for readily detachably connecting the garment supports with said lateral arms, so that garments draped over the supports extend outwardly to the garment receiving bar to be draped thereover to hang on opposite sides of the frame, and means for maintaining the garments in substantially the plane of the frame.

7. In a hand luggage of the case type including hingedly connected sections, a garment carrying frame hingedly mounted in one of the sections adjacent its hinged connection with the other to be movable to and from a position aligned with either section when the case is open, a transverse bar at one end of the frame and over which garments may be draped, individual garment supports adapted to have garments draped thereover preparatory to being draped over said transverse bar, and means at the other end of the garment carrying frame for mounting the individual garment supports in superimposed relationship.

8. In a hand luggage of the case type having hingedly connected sections, a garment carrying frame hingedly mounted adjacent the hinged connection of said sections for movement to and from a position aligned with either section when the case is open, a transverse garment receiving bar at one end of the frame, parallel laterally extending arms at the other end of the frame, and individual garment supports adapted to be detachably mounted on said laterally extended arms in superimposed relationship, garments draped over the garment sections extending to the other end of the frame and over the transverse bar.

9. In a hand luggage of the character described, including hingedly connected sections, a garment receiving frame comprising spaced side arms connected by a transverse garment receiving bar, means hingedly mounting the side arms for movement about an axis adjacent to and substantially parallel with the axis of the hinged connection between the sections, parallel lateral arms carried by the side arms at a point spaced from the transverse garment receiving bar, individual garment supports adapted to have garments draped thereover preparatory to being draped over the garment receiving bar, attaching means at the outer ends of the individual garment supports having apertures adapted to receive the lateral arms whereby the individual garment supports are detachably connectible with said garment carrying frame, and means at the outer ends of the lateral arms for preventing accidental detachment of the individual garment carrying supports.

10. In a hand luggage of the case type including hingedly connected sections, a gar-

ment carrying frame hingedly mounted for movement about an axis adjacent to and substantially parallel with the axis of the hinged connection between the sections, said garment receiving frame comprising side arms connected at their outer ends by a transverse garment receiving bar, substantially T shaped laterally extending arms carried by the side arms adjacent the hinged mounting of the garment carrying frame, and individual garment supports having slots at the outer ends adapted for engagement over the T shaped heads of the laterally extending arms, said T shaped heads of the laterally extending arms preventing accidental detachment of the garment supports.

In testimony whereof, I hereunto affix my signature.

GEORGE HENRY WHEARY.
